UNITED STATES PATENT OFFICE.

JAMES W. GIBSON, OF DENVER, COLORADO.

MOP.

Application filed April 14, 1928. Serial No. 270,124.

This invention relates to the class of brushing and scrubbing and pertains particularly to a mop head structure.

The primary object of the present invention is to provide in a manner as hereinafter set forth, an improved mop head designed to firmly grip and hold a mop rag, for scrubbing.

Another object of the invention is to provide, in a manner as hereinafter set forth, a mop head of strong and durable construction which can be easily and quickly manipulated to grasp or release a mop rag.

A still further object of the invention is to provide, in a manner as hereinafter set forth, a resilient mop rag gripping structure having a spring controlling a portion of the gripping element permitting the employment of hard and heavy mop rags or small rags as desired, the resilient element causing the firm gripping of the same.

The invention will be best understood from a consideration of the following detailed description taken in connection with the accompanying drawing forming a part of the present invention with the understanding, however, that the invention is not confined to any strict conformity with the showing of the drawing but may be changed or modified so long as such changes or modifications mark no material departure from the salient features of the invention as expressed in the appended claims.

In the drawing:

Figure 1 shows the mop head structure embodying the present invention, in front elevation.

Figure 2 is a vertical sectional view taken upon the line 2—2 of Figure 1.

Figure 3 is a view in rear elevation of the mop head structure.

Figure 4 is a detailed perspective view showing the structure in open position.

Figure 5 is a transverse section taken upon the line 5—5 of Figure 3.

Referring now to the drawing in detail wherein like numerals of reference indicate corresponding parts throughout the several views, the numeral 1 indicates a mop handle upon the lower end of which the mop rag gripping head embodying the present invention, is mounted.

Secured upon the end of the handle 1 is the head plate 2 which, as shown, is a relatively long body which is arranged transversely of the end of the handle and has

formed intermediate its ends upon one longitudinal edge, the short sleeve portion 3 which receives the end of the handle and to which it is secured by the rivets or other appropriate securing elements 4. This sleeve 3 is provided at diametrically opposite points with the laterally projecting ears 5. The longitudinal edge opposite that edge in which the sleeve 3 projects is formed to provide the groove or gutter 6 which is of V-shaped cross sectional design and in which a portion of the hereinafter described mop rag gripping yoke positions.

At each end of the head 2 there is formed a guide ear 7, the utility of which will be seen as the description of the structure proceeds.

The head plate 2 is here shown as formed of a pair of complementary members but, it is of course to be understood that this plate may be of solid construction as for example it may be cast in a solid piece.

Associated with the head 2 is a mop rag gripping yoke indicated as a whole by the numeral 8. This yoke comprises a straight cross portion 9 and the rearwardly extending converging legs 10. The legs 10 of the yoke portion extend through the guide ears 7 as shown and the straight transverse portion 9 thereof is designed to normally position in the groove 6 of the head 2.

In order to permit movement of the yoke 8 longitudinally of the handle 1 a portion of each leg 10 adjacent the cross portion 9 is made straight to extend parallel with the handle. This permits reciprocatory movement of the yoke, these straight portions, which are indicated by the numeral 7 sliding through the guide ears 7 as shown.

Slidably mounted upon the handle 1 is a pair of rings 12 and 13 each of these rings having the diametrically oppositely positioned outwardly extending headed arms 14 and 15. These rings further have fingers 16 formed about the edge thereof, the fingers of one ring being directed toward those of the opposite ring.

Surrounding the handle 1 and positioned between the rings 12 and 13 is a coiled spring 17, and connecting the ears 14 of the ring 12 with the underlying ears 15 of the rings 13 are longitudinally slotted connecting bars 18, the slots of these bars in which the ears are slidably positioned behind the heads thereof, being indicated by the numerals 19. These bars 18 prevent the spring 17 from forcing the rings beyond a predetermined distance.

apart but do not prevent compression of the spring and the movement of the rings toward one another.

The ears 15 further have pivotally connected thereto one end of a toggle arm 20, the other end of each of these arms being pivotally connected to one side of a lever member 21, adjacent the lower end of the same. This lever member 21 has at each side adjacent the pivotal connection therewith of a toggle arm 20, a longitudinally extending leg 22 which is pivotally mounted upon one of the ears 5 carried by the plate sleeve 3.

When the mop head is to be opened for the positioning of a mop rag between the bar 9 of the yoke member and the grooved edge 6 of the plate 2, the lever is swung outwardly from the handle 1 to the position shown in Figure 4, this movement swinging the lower ends of the toggle arms 20 outwardly and pulling down upon the same simultaneously thereby pulling the slotted bars 18 longitudinally of the handle 1 and forcing the yoke 8 to move in the same direction. As will be readily understood this causes the bar portion 9 of the yoke to move away from or out of the slot 6 in the plate 2. After the mop rag has been placed in position across the bar 9 and the lever 21 swung upwardly the reverse of the movement just described will be performed until the bar 9 draws the mop rag tight into the groove 6. When the mop rag has been tightly clamped between the bar 9 of the yoke and the plate 2 further movement of the yoke 8 longitudinally of the handle will be prevented but this will not prevent the turning of the toggle arm to a position substantially parallel with the handle for the lower ring 13 will be forced upwardly to compress the spring 17 against the upper ring 12 thus permitting the lever 21 to be swung back to a position substantially parallel with the handle 1 as shown in Figure 2.

From the foregoing description it will be readily seen that the mop head structure thus described can be readily and quickly manipulated to place a mop rag in position or to remove a mop rag from position and when a mop rag is being held by the head it will be secure against displacement.

Having thus described my invention what I claim is:

1. In a mop head structure, an elongated plate, means for securing said plate at the central portion of one longitudinal edge to a mop handle to extend transversely thereof, the other longitudinal edge of said plate being provided with a groove, guide ears carried by said plate one upon each end thereof, a pair of ring members designed to be traversed by a handle extending from the plate, laterally projecting ears carried by said rings, a spring element arranged between

said rings and normally forcing the same apart, longitudinally slotted bars connecting the ears of one ring member with the ears of the adjacent ring member, a substantially U-shaped yoke having the straight portion connecting the pair of leg portions, said straight portion being designed to extend longitudinally of said plate to position in said groove, said legs extending through said ears and longitudinally of a handle attached to the plate, and further having their ends connected to the ears of the ring member remote from the plate, and a lever member carried by said plate and having connection with the ears of the ring member lying adjacent the plate and designed, when actuated, to move the ring members, spring and yoke longitudinally of the handle, substantially as described.

2. In a mop head structure, an elongated plate, means for securing said plate in the central portion of one longitudinal edge to a mop handle to extend transversely thereof, the other longitudinal edge of said plate being provided with a groove, guide ears carried by said plate one upon each end thereof, a pair of ring members designed to be traversed by a handle extending from the plate, laterally projecting ears carried by said rings, a spring element arranged between said rings and normally forcing the same apart, longitudinally slotted bars connecting the ears of one ring member with the ears of the adjacent ring member, a substantially U-shaped yoke having the straight portion connecting the pair of leg portions, said straight portion being designed to extend longitudinally of said plate to position in said groove, said legs extending through said ears and longitudinally of a handle attached to the plate, a pair of toggle arms connected at one end to the ears of the ring member adjacent said plate, and a lever member pivotally attached at one end to said plate and having the other ends of said toggle arms pivotally connected thereto intermediate the ends thereof and designed, when swung, to shift the said rings, spring and yoke member longitudinally of the mop handle, substantially as described.

3. In a mop, a handle, a cross head secured to said handle provided with a pivot ear, an upper and a lower ring on said handle, an expansion spring confined between said rings, a bail slidably carried by the cross head for coaction therewith, means connecting the bail with the upper ring, a handle rockably mounted on said pivot ear, and a toggle link pivotally connected to said handle intermediate its ends and beyond said pivot point and to the lower ring, as and for the purpose specified.

In testimony whereof I affix my signature.
JAMES W. GIBSON.
